CLAIM

I claim the ornamental design for a vehicle seat, as shown and described.

DESCRIPTION

FIG. 1 is a perspective view of a vehicle seat.

FIG. 2 is a left side view of the vehicle seat.

FIG. 3 is a right side view of the vehicle seat.

FIG. 4 is a front view of the vehicle seat.

FIG. 5 is a rear view of the vehicle seat.

FIG. 6 is a top view of the vehicle seat; and,

FIG. 7 is a bottom view of the vehicle seat.

The broken line showing is for the purpose of illustrating portions of the vehicle seat and forms no part of the claimed design.
